CABINET FOR ELECTRONIC MEASURING AND TEST EQUIPMENT OR THE LIKE

John T. Paslawsky, 583 Ord Drive, Fairview Estates,
Boulder, Colo.

Filed June 8, 1964, Ser. No. 80,313

Term of patent 14 years

(Cl. D26—1)

FIG. 1

FIG. 2

FIGURE 1 is a top plan view of a cabinet for electronic measuring and test equipment or the like, showing my new design;

FIGURE 2 is a front elevational view;

FIGURE 3 is a rear elevational view;

FIGURE 4 is a bottom plan view; and

FIGURE 5 is a side elevational view, the opposite side being a mirror image thereof.

The dominant features of my design are shown in solid lines in the drawing. Portions of the drawing figures are diagonally lined to indicate transparency and portions are stippled to indicate opacity.

I claim:

The ornamental design for a cabinet for electronic measuring and test equipment or the like, as shown and described.
